(57) **CLAIM**

The ornamental design for a combined tablet computer case and easel, as shown and described.

DESCRIPTION

FIG. 1 is a perspective view of a combined tablet computer case and easel according to the present invention.

FIG. 2 is a front view of a combined tablet computer case and easel according to the present invention.

FIG. 3 is a back view of a combined tablet computer case and easel according to the present invention.

FIG. 4 left side view of a combined tablet computer case and easel according to the present invention.

FIG. 5 is a right side view of a combined tablet computer case and easel according to the present invention.

FIG. 6 is a top view of a combined tablet computer case and easel according to the present invention.

FIG. 7 is a bottom view of a combined tablet computer case and easel according to the present invention.

FIG. 8 is a perspective view of the combined tablet computer case and easel of FIG. 1 according to the present invention showing the handles retracted.

FIG. 9 is a front view of FIG. 8 according to the present invention.

FIG. 10 is a back view of FIG. 8 according to the present invention.

FIG. 11 left side view of FIG. 8 according to the present invention.

FIG. 12 is a right side view of FIG. 8 according to the present invention.

FIG. 13 is a top view of FIG. 8 according to the present invention.

FIG. 14 is a bottom view of a combined tablet computer case and easel according to the present invention.

FIG. 15 is a perspective view of a combined tablet computer case and easel according to the present invention in an open position with the easel extended.

FIG. 16 is a front view of a combined tablet computer case and easel according to the present invention in an open position with the easel extended.

FIG. 17 is a back view of a combined tablet computer case and easel according to the present invention in an open position with the easel extended.

FIG. 18 is a left side view of a combined tablet computer case and easel according to the present invention in an open position with the easel extended.

FIG. 19 is a right side view of a combined tablet computer case and easel according to the present invention in an open position with the easel extended.

FIG. 20 is a top view of a combined tablet computer case and easel according to the present invention in an open position with the easel extended; and,

FIG. 21 is a bottom view of a combined tablet computer case and easel according to the present invention in an open position with the easel extended.

The broken lines illustrate stitching and form part of the claimed design.
